UNITED STATES PATENT OFFICE.

JOHN C. FREDRICKSEN, OF MILLER, INDIANA.

INTERNAL-COMBUSTION ENGINE.

1,406,839.

Specification of Letters Patent. Patented Feb. 14, 1922.

Application filed April 9, 1918. Serial No. 227,470.

To all whom it may concern:

Be it known that I, JOHN C. FREDRICKSEN, a citizen of the United States, and a resident of the city of Miller, county of 5 Lake, and State of Indiana, have invented certain new and useful Improvements in Internal-Combustion Engines, of which the following is a specification.

My invention relates to improvements in 10 internal combustion engines, and has for its object the provision of improved means for controlling and operating the exhaust valve thereof.

The invention consists in the combinations 15 and arrangements of parts hereinafter described and claimed.

The invention will be best understood by the accompanying drawing forming a part of this specification, and which is a vertical 20 section of an internal combustion engine cylinder embodying the invention.

The preferred form of construction is illustrated in the drawing comprising an explosive engine cylinder 1, having a piston 2 operating therein and connected by a 25 connecting rod 3 with the crank shaft 4 thereof.

An intake passage is formed in the head 30 of cylinder 1 and is controlled by suction operating intake valves 6 as indicated, a suitable spark plug 7 being also provided in the head of said cylinder. Transversely aligning valve cylinders 8 and 9 are arranged in the walls of cylinder 1 and pistons 10 and 11 are arranged to operate therein. The pistons 10 and 11 are mounted on a piston 13 operating in a dash pot cylinder 14 arranged at one side of cylinder 1 and provided at each end with minute air escape 40 ports or openings 15 for cushioning the movement of the pistons 10 and 11 in each direction.

A movable plug 9' is also provided for giving access to cylinders 9 and 8. An exhaust port 16 leads to the outer end of cylinder 8, the walls of which are also provided with slots 17 acting also as exhaust ports controlled by piston 10 to permit exhaust of cylinder 1. The inner end of cylinder 1 is 45 provided with a piston controlled port 19 located at the inner end of the stroke of piston 2 and whereby at the inner end of the stroke of said piston, the combustion pressure remaining in cylinder 1 is admitted to 50 the outer end of cylinder 8 to operate piston 10 to open the exhaust through ports 17

and 16, the combustion pressure on the inner faces the pistons 10 and 11, being opposite and balanced.

A passage 20 in the wall of cylinder 1 60 leads to a port 21, as indicated, arranged to co-operate with by-pass passages 22 and 23 positioned in the walls of piston 2. An annular air compressing cylinder or space 24 is formed in the inner portion of the walls 65 of cylinder 1 and an annular air compressing piston head 25 on piston 2 operates therein as shown. Air ports 26 are arranged centrally in the walls of cylinder 24, establishing free communication with the atmosphere. By this means and arrangement, at the inner end of each stroke of the piston 2, the cylinder 9 is exhausted into cylinder 24 by by-pass 22 to permit the opening of piston 10 for the exhaust as explained above. 70 On the reverse movement of piston 2, after port 26 is passed, air is compressed in cylinder 24 which is admitted by by-pass 23 into port 21 and passage 20, and consequently into cylinder 9 to close the exhaust 75 ports 16—17. On the intake and the compression stroke of piston 2, valve 10 is unaffected by the conditions in cylinder 1 as will be readily understood.

The arrangements set forth constitutes a 80 simple, automatic, positive and efficient means for controlling and effecting the complete exhaust of the engine cylinder.

While I have illustrated and described the preferred form of construction for carrying 90 my invention into effect, this is capable of variation and modification without departing from the spirit of the invention. I therefore, do not wish to be limited to the precise details of construction set forth, but 95 desire to avail myself of such variations and modifications as come within the scope of the appended claims.

Having described my invention, what I claim as new and desire to secure by Letters Patent is:—

1. An internal combustion engine, comprising an engine cylinder and a reciprocating engine piston operating therein; transversely aligning valve cylinders in the walls 105 of and projecting into said engine cylinder, there being an exhaust port connected with the outer end of one of said valve cylinders, and there being exhaust ports in the walls of said one-valve cylinder; valve pistons 110 operating in said valve cylinders; a piston rod connecting said valve pistons; and a

port and passage in the wall of said engine cylinder, controlled by the engine piston and communicating with the outer end of said one-valve cylinder; and automatic means 5 for closing said one-valve cylinder, substantially as described.

2. An internal combustion engine comprising a cylinder; a reciprocating piston exhaust valve therefor; a piston controlled 10 port for utilizing the combustion pressure of said cylinder for moving said exhaust valve to open said valve; and means on the cylinder piston for compressing and utilizing air to move said valve in the opposite 15 direction to close the same, substantially as described.

3. An internal combustion engine comprising a cylinder and a reciprocating piston operating in said cylinder; a suction 20 controlled intake for said cylinder; transversely aligning valve cylinders in the walls of said engine cylinder, there being an exhaust port connected with the outer end of one of said valve cylinders; exhaust ports in 25 the wall of said valve cylinders; pistons operating in said valve cylinders; a piston rod connecting said valve pistons; a dash pot operating on said piston rod; a piston controlled port and passage in the wall of said engine 30 cylinder communicating with the outer end of the valve cylinder provided with the exhaust ports; and means controlled by the engine piston for periodically compressing and admitting compressed air to the other 35 valve cylinder for closing the exhaust, substantially as described.

4. An internal combustion engine comprising a cylinder and a reciprocating piston operating in said cylinder; a suction con-

trolled intake for said cylinder; trans- 40 versely aligning valve cylinders in the walls of said engine cylinder, there being an exhaust port connected with the outer end of one of said valve cylinders; exhaust ports in the wall of said valve cylinders; pistons 45 operating in said valve cylinders; a piston rod connecting said valve pistons; a dash pot operating on said piston rod; a piston controlled port and passage in the wall of said engine cylinder communicating with 50 the outer end of the valve cylinder provided with the exhaust ports; an annular air compressing piston at the inner end of the engine piston, there being an annular air compressing cylinder located in the walls of the 55 engine cylinder co-operating with said air compressing piston, and having a central port communicating with the atmosphere; a port and a passage in the wall of said engine cylinder connecting the outer end of 60 the valve cylinder opposite the one provided with the exhaust ports with a point in the wall of said engine cylinder closely adjacent the outer end of said air compressing cylinder; and by-pass passages in the walls 65 of said engine piston arranged to throw said last mentioned port into communication with said air compressing cylinder at opposite ends of the stroke of said engine piston, substantially as described. 70

In testimony whereof I have signed my name to this specification in the presence of the subscribing witnesses.

JOHN C. FREDRICKSEN.
